UNITED STATES PATENT OFFICE.

RAYMOND E. DODGE, OF DERBY, CONNECTICUT, ASSIGNOR OF ONE-HALF TO CYRUS BREWSTER, OF DERBY, CONNECTICUT.

MACHINE FOR APPLYING STRIPS OF TAPE TO FABRIC.

No. 882,779.

Specification of Letters Patent. Patented March 24, 1908.

Application filed January 2, 1908. Serial No. 408,949.

To all whom it may concern:

Be it known that I, RAYMOND E. DODGE, a citizen of the United States, residing at Derby, in the county of New Haven and 5 State of Connecticut, have invented a new and useful Improvement in Machines for Applying Strips of Tape to Fabric; and I do hereby declare the following, when taken in connection with the accompanying drawings and the letters of reference marked 10 thereon, to be a full, clear, and exact description of the same, and which said drawings constitute part of this specification, and represent, in—

15 Figure 1 a front view partially in section of a machine constructed in accordance with my invention. Fig. 2 a top or plan view of the same with the tape-carrying means broken away. Fig. 3 a sectional view on the line 20 *a*—*b* of Fig. 1 on an enlarged scale. Fig. 4 a broken side view of a foot illustrating the means for lifting the upper feed roll.

This invention relates to an improvement 25 in machines for applying strips of tape to fabric.

In the manufacture of garments, and particularly corsets, strips of tape are applied at certain points for the purpose of stiffening or shaping the garment, and in the usual 30 construction of the corsets these strips are first basted and subsequently stitched.

The object of this invention is to provide 35 a machine by which the strips may be glued or pasted in place to avoid the necessity of basting; and the invention consists in the construction hereinafter described and particularly recited in the claims.

In general form the frame of the machine 40 is on the order of the frame of a sewing machine comprising a plate or table 2, an upper arm 3 parallel therewith and projecting from a vertically arranged post 4 in which the gearing is mounted. At the outer end of the arm is a depending foot or bracket 5 in 45 which is mounted an upper feed roll 6 preferably in yielding bearing. In the table below the roll 6 is a slot 7 and mounted in brackets 8 below the table is a roller 9 which projects slightly above the face of the table. 50 This roller 9 is mounted on a shaft 10 which I will call the lower shaft and this shaft carries a pinion 11 which meshes with a pinion 12 on the driving shaft 13 which is driven by a belt pulley 14 in the usual way. Ex- 55 tending through the upper arm 3 of the

frame is a shaft 15 which I will call the upper shaft, and this carries a pinion 16 which meshes with an intermediate pinion 17 which is driven by the pinion 12.

On the shaft 15 is a beveled gear 18 meshing with a beveled gear 19 on a vertically arranged shaft 20 which shaft at its lower end carries a beveled pinion 21 meshing with a beveled pinion 22 on the axle 23 of the roll 6 so that the roll 6 is driven in one 60 direction and the roll 9 in the opposite direction. Arranged above the arm 3 is a tank 24 containing glue or other suitable adhesive material and in this tank and running in the material is a pasting roll 25 65 formed in its circumferential face with pockets 26 more or less in number, to pick up and carry the adhesive material. This pasting roll 25 is mounted on a shaft 40 which is driven by a belt 41 from the driving 70 shaft 13. Also mounted on the upper arm 3 is a vertically arranged post 27 having at its top a cross arm 28 supporting at the outer ends rollers 29 and 30. Secured to the upper edge of the tank 24 are shafts 31, 32 75 carrying idle rollers 33 and 34. Mounted on the shaft 31 is a stripper 35 which removes surplus adhesive material from the feed roll 25.

Mounted in the post 27 is a horizontal arm 85 36 which supports a spool 37 of tape or other suitable material, the strip of tape 38 passing from the roll down around the idler 34 over the pasting roll 25, thence under the idler 33 up over the idlers 30 and 29, and thence 90 down to the feed roll 6, the pasted side being downward. Preferably and as herein shown a stripper 39 will be arranged below the bed and in contact with the lower feed roll 9. Preferably and as herein shown, the foot 5 95 is cut away to receive a bearing block 48 which is held in place by springs 49. This block bearing upon the ends of the axle 23 of the roll 6 yieldingly holds the roll in place. To lift the roll for the insertion of goods beneath it, I employ a bell crank lever 42 which is pivoted as at 43 to the lower portion of the foot 5, and the arm 44 projects beneath the ends of the axle 23. Pivoted to the upper portion of the foot is an eccentric 100 45 provided with an operating handle 46 by which it may be turned against the upwardly extending arm 47 of the bell crank lever and so that by turning the handle 46 forward the cam 45 is rocked, throwing 110

the arm 47 rearward and the arm 44 upward, leaving the axle against the tension of the springs 41. To provide for lifting the axle the beveled pinion 21 is keyed to the shaft 20 so as to move vertically thereon. The strip having thus been pasted and brought to the feed rolls, a garment is passed between the rolls, and the pasted strip is pressed thereon. The strip is thus secured in place until it can be stitched in the usual manner.

I claim:—

1. In a machine for applying strips of tape to fabric comprising a table, an upper arm, a depending foot carried by the outer end of said arm, a feed roll mounted therein, a lower shaft beneath the table, and a feed roll carried thereby in line with the upper feed roll, an upper shaft, means for driving the upper and lower shafts, connections with the upper shaft for driving the upper roll, a paste tank, a pasting roll mounted therein, and means for supporting a roll of tape and conducting the same over the face of the pasting roll and between the said feed rolls, substantially as described.

2. In a machine for applying strips of tape to fabric comprising a table, an upper arm, a depending foot carried by the outer end of said arm, a feed roll mounted therein, a lower shaft beneath the table and a feed roll carried thereby in line with the upper feed

roll, an upper shaft extending through the upper arm, means for driving the upper and lower shafts, connections with the upper shaft for driving the said upper roll, a paste tank, a pasting roll mounted therein and formed in its face with paste pockets, means for driving said pasting roll, an upright post having cross-arms, idler rolls carried by 35 said arms, idlers carried by the upper edge of said paste tank, a roll of tape mounted above the tank and adapted to be passed over the pasting roll and between the feed rolls, substantially as described.

3. A machine for applying strips of tape to fabric, comprising a table, an upper arm, a depending foot carried by the outer end of said arm, a feed roller supported in said foot, a bell crank lever pivoted to the foot 50 and having an arm projecting beneath the shaft of the upper roller, an eccentric for turning the said bell crank lever, means for driving said feed rolls, and means for applying paste to the face of the strip and conducting the pasted strip to the feed rolls, substantially as described.

In testimony whereof, I have signed this specification in the presence of two subscribing witnesses.

RAYMOND E. DODGE.
